UNITED STATES PATENT OFFICE.

MILTON J. GREENMAN AND HORACE JAYNE, OF PHILADELPHIA,
PENNSYLVANIA.

DISPLAY-RECEPTACLE FOR OBJECTS IMMERSED IN PRESERVATIVE LIQUIDS.

SPECIFICATION forming part of Letters Patent No. 774,420, dated November 8, 1904.

Application filed March 10, 1904. Serial No. 197,424. (No model.)

To all whom it may concern:

Be it known that we, MILTON J. GREENMAN and HORACE JAYNE, both of Philadelphia, in the county of Philadelphia and State of Pennsylvania, have invented certain new and useful Improvements in Display-Receptacles for Objects Immersed in Preservative Liquid, whereof the following is a specification, reference being had to the accompanying drawings.

For the display of objects immersed in liquid it is desirable that the receptacle be completely filled with the liquid; otherwise the line of vision is liable to be distorted by diffraction; but, on the other hand, a closed receptacle completely filled with liquid is liable to alternately leak or acquire air-bubbles by reason of the expansion or contraction of the liquid due to changes in temperature.

Our invention relates to a display-receptacle in which this difficulty is overcome by the provision of an auxiliary compartment communicating with the display-compartment, but so placed as not to interfere with the examination of the object displayed. In this way the display-compartment may be completely filled with preservative liquid, while the auxiliary compartment is but partially filled, a sufficient amount of air remaining therein to allow for the expansion or contraction of the liquid.

Furthermore, by our invention we dispense with all packed or cemented joints and rely upon the simple opposition of the receptacle and its cover with maintenance of sufficient compression between the two by clamping mechanism. In this way we avoid the difficulties which have heretofore been experienced from the cracking and disintegrating of packed or cemented joints, all of which are peculiarly liable to destructive processes when used in contact with a preservative liquid in which an organic specimen is contained.

Our invention is further advantageous in providing a construction which, though not easily tampered with, yet affords a ready means by which at proper intervals the liquid that it contains may be drawn off and replaced.

In the accompanying drawings, Figure I is

a plan view of a display-receptacle embodying our invention. Fig. II is a vertical longitudinal section along the line II II in Fig. I. Fig. III is an end elevation of the same, and Fig. IV is a transverse vertical section along 55 the line IV IV of Fig. I and Fig. II.

In said figures 1, is the main body of the receptacle. It may be made of glass, porcelain, or other suitable material. Its contour may be adapted to the general shape and nature 60 of the object to be displayed within it. It is divided by a partition 2 into two compartments, which may be termed, respectively, the "main" or "display" compartment and the "auxiliary" compartment. The partition 2 is 65 pierced by an aperture 3, near the bottom, said aperture being preferably arranged centrally and inclined, as shown in Fig. II. The upper edge of the partition 2 is flush with the upper surface of a horizontal flange 4, formed 70 around the exterior of the upper edge of the receptacle. A glass cover-plate 5, corresponding in outline to the receptacle, rests on top of it and forms the cover for both of its compartments.

6 is a metallic frame similar in contour to the cover-plate and resting upon it. It is cut away to register with the display-compartment. It is preferably left intact where it covers the auxiliary compartment except 80 for a small opening 7, protected by a cap 8, attached to the frame by screws. The perimeter of the frame is provided with a depending flange 9, fitting around the cover-plate 5 and the edge flange 4 of the receptacle. At 85 intervals upon the lower edge of this flange 9 lugs 10 are attached thereto by screws.

A ground-opening 11 is provided in the cover-plate 5 over the auxiliary compartment, and this opening is fitted with a glass stopper 90 12, the head of which extends into and is protected by the cap 8.

The interior of the display-compartment may be provided with any convenient device for the mounting of the object to be displayed. 95 For many purposes it is convenient to employ a glass plate 13 as a mount, and we have accordingly shown our invention with provision for the support of such a plate consisting of glass supports 15, the ends of which 100

fit between paired vertical ridges 14 14, formed at intervals on the long sides of the display-compartment of the receptacle; but it will be understood that other means may be resorted to for the mounting or support of the object to be displayed within the receptacle.

In use the object to be displayed is first suitably attached to the plate 13, as by threads passing through small holes bored in it. The plate is then put in place within the receptacle, the supports 15 being chosen of the proper height having relation to the size and shape of the object. Both compartments of the receptacle are then filled to overflowing with the preservative liquid. The cover-plate 5 is then laid on the receptacle, care being taken to exclude all air-bubbles. The frame 6 is then adjusted upon the cover-plate and receptacle, and the two are clamped together around their perimeters by screwing up the lugs 10. Small rubber or felt pads 16 may be interposed between the lugs and the lower side of the flange 4, and likewise a pad or washer 17 may be interposed between the frame 25 and the upper edge of the plate 5. No packing or cement need be applied between the opposing surfaces of the receptacle and the plate 5, reliance being placed solely upon the tightness of the joint formed by the compression of the two together by means described. After these parts have all been properly adjusted a sufficient quantity of liquid is removed from the auxiliary compartment through the aperture 11, which is then closed by the stopper 12, which is in turn protected by screwing down the cap 8. In this condition our device will last for many years and withstand severe changes of temperature without leakage or disarrangement. Any expansion or contraction of the liquid is taken up by the air-cushion contained in the auxiliary compartment, the main display-compartment being thus maintained completely filled with liquid and with no air-bubbles or air layer to interfere with the proper inspection of the contained object. As there is no cement or packing between the opposing surfaces of the receptacle and the cover-plate, there is no way in which the liquid can have any chemical effect upon the joint, which consequently remains firm and efficient. If after a lapse of time it is desired to change the liquid—as, for instance, on account of its discoloration—it can be done by opening the aperture 11.

It is evident that the shape of the display-compartment may be much varied, and also the position and shape of the auxiliary compartment may be adapted according to convenience and circumstances.

60

Having thus described our invention, we claim—

1. A display-receptacle divided into a main and an auxiliary compartment; means for tightly covering both compartments; and means for maintaining communication between the liquid in the two compartments.

2. A display-receptacle divided by a partition into a main and an auxiliary compartment, the former being completely and the latter partially filled with preservative liquid; means for tightly covering both compartments; and means for maintaining communication between the two bodies of liquid below the level at which the liquid stands in the auxiliary compartment.

3. A display-receptacle, divided by a partition into a main and an auxiliary compartment; a single cover-plate closing both compartments; means for clamping the cover-plate to the receptacle; an aperture in the partition connecting the two compartments; and an aperture in the cover-plate over the auxiliary compartment, with means for closing the same.

80

4. In a two-compartment display-receptacle, a cover-plate closing both compartments; a flange around the upper edge of the receptacle corresponding in outline to the cover-plate; a frame fitting said cover-plate; and clamping means attached to said frame whereby the cover-plate is clamped to the top of the receptacle.

85

5. In a two-compartment display-receptacle, a cover-plate closing both compartments; a stoppered aperture in the cover-plate over one of the compartments; a frame surrounding the edges of both cover-plate and receptacle, and clamping the two together; and a removable cap attached to the frame protecting the stoppered aperture in the cover-plate.

95

In testimony whereof we have hereunto signed our names, at Philadelphia, Pennsylvania, this 8th day of March, 1904.

MILTON J. GREENMAN.
HORACE JAYNE.
